CUTTER

Robert Bruce Eaton, Des Moines, Iowa

Application May 12, 1941, Serial No. 393,047

7 Claims. (Cl. 30—335)

This invention relates to cutting and scraping devices. More specifically, it relates to such devices in which a razor blade is employed as the cutting or scraping edge. It further relates to holders for razor blades.

The problem of disposing of used razor blades is well known. Further it is an economic waste to discard these blades which are no longer sufficiently sharp to be used for shaving, for they still retain an edge amply sharp for cutting most materials. They are normally compounded from reasonably high quality steel and are therefore capable of retaining an edge for substantial periods of time which is satisfactory for most cutting operations. I have devised a novel cutting tool employing as the cutting edge a razor blade of the single edge type. Of course, members other than razor blades may be employed in my tool, but razor blades are normally the most available source for the cutting blade. Other cutting tools employing razor blades have been produced in the past but these commonly require tightening of screws or nuts in order to insure retaining the blade within the holder and they do not normally provide means for shielding the cutting edge when not in use.

My novel tool includes a handle consisting of a stock member suitably formed at one end according to my invention for receiving and retaining a razor blade, a razor blade, and a clasp member for aiding in retaining the razor blade in operative relationship to said stock. I have found that an elongated stick of plastic material serves very well as the base from which to fabricate my stock member. Obviously, of course, any other suitable material may be employed. The blade engaging the portion of the stock is formed by providing a channel extending inwardly from one end of the stock and by providing a relatively narrow slit extending longitudinally of the stock and providing communication between the said channel and the outside of the stock. When operatively assembled, the enlarged or reinforced section of the common single edge blade is received in the channel provided and the thin section of the blade extends outwardly through the slit described. A suitable clasp is provided for yieldably retaining the blade in position.

It is an object of this invention to provide a novel cutting tool employing a single edge type razor blade or similar member as the cutting edge.

Another object of this invention is to provide

a novel handle or holder for single edge razor blades.

Still another object of this invention is to provide such a holder capable of securely retaining the blade in operative position and capable also of receiving the blade in such a manner as to protect its cutting edge when not desired for use.

A still further object of this invention is to provide a cutting tool in which the cutting member may be changed from operative to inoperative position or vice versa with facility.

In order that a more clear and concise understanding of my invention may be had, reference should be made to the accompanying drawing, forming a part of this specification, in which:

Fig. 1 is a side elevation of one embodiment of my cutting tool with the cutting member in inoperative position.

Fig. 2 is a side elevation of the structure shown in Fig. 1 with the cutting member in operative position.

Fig. 3 is an enlarged front end view of the structure as shown in Fig. 2.

Fig. 4 is an enlarged cross sectional view taken on line 4—4 of Fig. 2.

Fig. 5 is a fragmentary enlarged bottom view of the handle member free of a cutting member.

Referring more specifically to the drawing, I have used the numeral 10 to designate the holder or handle portion generally. 11 designates the stock in the forward end 12 of which the razor blade 13 or other cutting member is received. In the forward end 12 of the stock 11 is provided a channel 14 extending longitudinally of the stock 11 and having its forward end communicating through the forward end of the portion 12 of the stock 11. A slit 15 extending largely co-extensive with the channel 14 provides means of communication through the wall structure of the channel 14 to the outside along the bottom side of the forward end portion 12 of the stock 11. When in operative position, the enlarged or reinforced portion 16 of the razor blade 13 is received within the channel 14 and the thin section 17 of the blade 13 extends outwardly through and past the slit 15 to expose the cutting edge 18. As appears clearly in Fig. 2, not the entire longitudinal extension of the enlarged portion 16 of the blade 13 is received in the channel 14 when the blade is in operative position. Clearly, since the enlarged section 16 of the blade 13 is of a thickness greater than the width of the slit 15, the blade 13 cannot

become disengaged from the holder 10 through transverse movement. A clasp member 19 is provided for limiting longitudinal movement of the blade 13 in the channel 14 whereby disengagement of the blade 13 from the holder 10 by longitudinal movement is controlled. The clasp means 19 which I have shown in the drawing resembles somewhat an elongated watch bow or a clevis and has inturned ends 20 and 21 which pivotally engage the recessed or restricted portions 22 and 23 of the forward end portion 12. The end portions 21 and 22 may extend through the restricted portions 22 and 23 into the channel 14, but such is not essential. In fact, it is not at all essential to my invention that the forward end portion 12 be restricted as at 22 and 23. When in operative position, a portion of the blade 13 extends beyond the forward end portion 12 of the stock 11 and the clasp member 19 engages the notch 24 in the blade 13. Since in the normal cutting movement power is applied to the handle with the handle in a position either substantially lateral from the cutting member or slightly forward from the cutting member, the blade 13 in my construction is securely supported in all directions necessary for successful operation as a cutting tool.

When the holder 11 is traveling substantially lateral of the blade 13 in the cutting movement, the enlarged section 16 of the blade 13 is bearing largely against that portion of the wall structure of the channel 14 which is substantially opposite the slit 15. When the holder portion 11 is traveling slightly forward of the blade 13, the blade is bearing partially against the upper wall structure of the channel 14 partially against that portion of the wall structure of the channel 14 which is adjacent the slit 15 and partially against the fastening member 19. When the blade 13 is in inoperative position, the cutting edge and a substantial portion of the thin section 17 of the blade is received in the channel 14 as appears clearly in Fig. 1. Other portions of the thin section 17 are positioned within the slit 15 and the outer edge of the enlarged section 16 is engaged by the fastening means 19 substantially in the manner shown in Fig. 1. In the inoperative position, the blade does not normally extend beyond the forward end of the portion 12. The clasp 19 engaging the blade 13 in the manner shown in Fig. 1 prevents the blade from becoming disengaged from the holder as a result of that portion of the thin section 17 contained in the channel 14 sliding outwardly through the slit 15.

In assembling my cutter, the enlarged portion 16 of the razor blade 13 and that portion of the thin section 17 which is adjacent said enlarged portion 16 are introduced into the forward ends of the channel 14 and slit 15 being certain that the clasp member 19 is to the enlarged section edge of the blade 13. The blade 13 is slid longitudinally backwardly into the channel 14 and slit 15 to a point such that it is possible to swing the fastening member 19 to a position such that its outer loop portion is forward of the forward-most end of the blade 13. The blade 13 is then slid forwardly until the notch 24 is engaged by the outer loop section of the fastener 19 as appears clearly in Fig. 2. In disassembling, the blade is slid backwardly until the notch 24 disengages the fastener 19 and it is possible to swing said fastener to the side of the enlarged portion 16 edge of the blade whereupon the blade is slid longitudinally forward until it disengages the

channel and slit. In placing the blade in inoperative position in the holder the fastening member 19 is swung so that its outer loop portion is to the slit side of the forward portion 12. The thin section 17 of the blade 13 is then introduced into the channel and slit with the cutting edge adjacent that wall of the channel 14 which is substantially opposite the slit 15. The blade is then slid rearwardly, the fastener 19 being so stationed that its outer loop portion is to the outer edge of the enlarged section 16.

The term "stock" is used in this specification and claims to designate the member in my tool which is grasped by the user and which has in its forward end portion structure adapted to receiving, at least in part, the cutting member. "Bottom" as used herein is intended to designate that surface of the holder on which the slit 15 opens and correspondingly positioned surfaces on other members.

My cutter has a variety of uses not only in the kitchen as a chopper and peeler, but also in the household in connection with seamstress work such as ripping, marking and cutting. The tool also has wide application in commercial fields especially in cutting wrappings on packages and the like and in cutting up cardboard boxes and similar materials.

The size of the channel 14 may be varied and need only be sufficient to receive the enlarged section of the cutting member. If larger than this, grooves may be provided adjacent the slit 15 on either side thereof and extending longitudinally therewith capable of receiving the bottom edges of the enlarged section 16 when the same is in operative position. The clasp 19 may be of any suitable nature. For example, a "half" loop suitably mounted and pivoted might be employed.

Other suitable control means may be substituted for the notch 24 or said notch may be omitted. If a loop member be employed as the clasp 19, it may be varied in size. The length of the channel and slit may be varied if they are sufficiently long, the loop 19 may be to either edge of the blade when it is being inserted into the handle.

I have described a specific embodiment of my invention for illustrative purposes, but it is apparent that one skilled in the art will be able to make certain modifications and variations in the structure as described and this without departing from the spirit and scope of my invention, I therefore wish to be limited herein only by the appended claims.

I claim:

1. A handle for a cutting tool comprising a stock, a largely closed channel extending inwardly into said stock from one end thereof, a narrow slit extending longitudinally of said stock connecting said channel with the outside of said stock, and a clasp member on said stock capable of engaging an end of a blade to at least aid in retaining it in said slit.

2. A handle for a cutting tool comprising a stock, a deep narrow groove extending for a distance longitudinally of said stock from one end thereof, a longitudinally extending enlarged section in that portion of said groove which is in the interior of said stock extending to the adjacent end of said stock, and a clasp member on said stock capable of engaging an end of a blade to at least aid in retaining it in said groove.

3. A handle for a cutting tool comprising a stock, a largely closed channel extending in-

wardly into said stock from one end thereof, a narrow slit extending longitudinally of said stock connecting said channel with the outside of said stock, and a generally bow-shaped member having inturned ends so pivotally mounted on said stock that said bow's outer loop portion is capable of swinging to a position forward of that end of the stock on which said channel opens and is capable also of swinging to a position such that its inner surface is substantially facing said slit. 10

4. A handle for a cutting tool comprising a stock, a largely closed channel extending inwardly into said stock from one end thereof, a narrow slit extending longitudinally of said stock connecting said channel with the outside of said stock, restricted areas on the outer surface of said stock on each side of said channel and slit extending to the adjacent end of said stock, and a generally bow-shaped member having inturned ends so pivotally mounted on said restricted 20 areas of said stock that said bow's outer loop portion is capable of swinging to a position forward of the adjacent end of the stock and is capable also of swinging to a position such that its inner surface is substantially facing said slit.

5. A cutter comprising a stock, a largely closed channel extending inwardly into said stock from one end thereof, a narrow slit extending longitudinally of said stock connecting said channel with the outside of said stock, a blade member having an enlarged section at least partially received in said channel and longitudinally slideable therein and having a thin section at least a part of which extends through said slit and which supports a cutting edge outside the bounds 30 35

of said stock, and a clasp member on said stock capable of engaging an end of said blade to at least aid in retaining it in said slit and channel.

6. A cutter comprising a stock, a largely closed channel extending inwardly into said stock from one end thereof, a narrow slit extending longitudinally of said stock connecting said channel with the outside of said stock, a blade member having an enlarged section at least partially received in said channel and longitudinally slideable therein and having a thin section at least a part of which extends through said slit and which supports a cutting edge outside the bounds of said stock, a clasp member on said stock capable of engaging the outer forward end of said blade to at least aid in retaining said blade in said slit and channel, and means on the forward end of said blade for controlling the position of said clasp. 15

7. A cutter comprising a stock, a largely closed channel extending inwardly into said stock from one end thereof, a narrow slit extending longitudinally of said stock connecting said channel with the outside of said stock, a blade member having an enlarged section at least partially received in said channel and longitudinally slideable therein and having a thin section at least a part of which extends through said slit and which supports a cutting edge outside the bounds of said stock, a generally bow-shaped member having inturned ends pivotally mounted on said stock and capable of engaging the forward end of said blade, and a notch on the forward end of said blade for controlling the position of said bow. 25 30
